UNITED STATES PATENT OFFICE.

WILLIAM J. BALDWIN, OF BROOKLYN, NEW YORK.

DEVICE FOR FEEDING FUEL TO FURNACES.

SPECIFICATION forming part of Letters Patent No. 681,429, dated August 27, 1901.

Application filed December 24, 1900. Serial No. 40,868. (No model.)

To all whom it may concern:

Be it known that I, WILLIAM J. BALDWIN, a citizen of the United States of America, and a resident of the borough of Brooklyn, in the city of New York and State of New York, have invented certain new and useful Improvements in Devices for Feeding Fuel to Furnaces, of which the following is a specification.

10 This invention relates to improvements in devices for feeding fuels to furnaces. In particular it relates to hoppers for feeding light and inflammable refuse materials—such as paper, paper boxes, pieces of wooden packing-boxes, and other light inflammable materials—into subsidiary furnaces, such as are described in my application for patent of the United States filed July 2, 1900, Serial No. 22,277, and now pending.

20 The invention also relates to certain improvements in the construction of the furnace itself, as hereinafter described.

In using fuels of the character mentioned it is desirable that a receptacle should be provided at the furnace-door or that the door itself should constitute such a receptacle for receiving such materials in bulk and readily and quickly discharging them into the furnace and that the door-opening in the furnace-front should be closed during the interval required to dump the materials into the furnace in order to prevent the possibility of the escape of flames from the door. It is also desirable that the furnace be so constructed as to admit large quantities of air above the burning fuel. I attain these objects by providing at the said door-opening a hopper which constitutes both a door for the furnace and a receptacle to receive the fuel material and dump it into the furnace, and this hopper is so constructed and shaped that it closes the door-opening both in its normal position—that is, when serving as a door and to receive the fuel materials—and also in its dumping position. I also by preference combine with the hopper a hood which closes the door-opening during the motion of the hopper from one of its positions to the other, and thus prevent the escape of the flames from the opening that is left around the hopper in its intermediate positions. I also provide twyvers in the front

of the furnace above the grates to admit air into the furnace above the burning fuel.

Referring to the drawings which accompany this specification to aid the description, 55 Figure 1 is a longitudinal vertical section of a furnace equipped with my hopper. The hopper is shown in the normal position, wherein it constitutes a door. Fig. 2 is a front elevation and cross-section of the furnace.

A is any furnace which is suitable for light fuels, a being an opening which connects to the chimney or to the flue which leads to the main furnace or furnaces, as described in my said application Serial No. 22,277. In front 65 the brickwork is preferably inclined downward from the door, as indicated at b, to allow the metal hopper C to take an effective dumping position. Said hopper C is provided with a horizontal cross-shaft c, the round ends 70 of which turn in bearings d, which are fixed on the furnace-front e. On the projecting ends of said shaft c are preferably fixed counterweights f. Said hopper C is provided with a wall h, which constitutes a door to 75 close the door-opening in the front of the furnace when the said hopper is in the normal position of Fig. 1, and with a wall i, which is of such shape and at such an angle with the wall h that when said hopper has turned to 80 the dumping position said wall i or the edges thereof shall also close said door-opening and prevent the escape of flames while the hopper is dumping the fuel into the furnace, and I prefer to arrange the said walls h and i at an 85 obtuse angle with each other, as shown in Fig. 1, and so that when the said hopper C is in the dumping position the said wall h shall incline parallel with and rest on the brick-work b and at such an angle that the fuel will 90 slide down said wall and upon the inclined grates m. The front wall j of said hopper C is preferably curved on an arc struck from the shaft c as a center and is high enough to extend to the platform w when the hopper is 95 in the normal position. Said hopper C is of course of such length parallel to the furnace-front as to extend across the door-opening and is in general of rectangular shape in plan. The end walls l of said hopper are each pref- 100 erably curved at their upper edge on an arc of a circle which is struck from said shaft c

as a center, and said end walls *l* may either be of one piece, as shown, or the curved top pieces may be bolted to the main end pieces.

Any suitable device may be provided for 5 moving the hopper *C*, as a curved rack *n*, which is fixed on an end of the said hopper, and a pinion *o*, meshing therewith and fixed on a shaft *p*, which is carried in suitable bearings on the furnace-front and is provided 10 with a handle, as indicated.

I prefer to provide a buffer *q* to arrest the motion of the hopper when coming to its normal position, said buffer *q* consisting of a coiled spring in the belled end of a tube 15 which is fixed to the furnace-front *e* at a suitable angle. The front wall *h* of said hopper *C* is protected in any suitable manner, as by a fire-brick lining, from the heat of the flames.

The material is brought to the hopper *C* on 20 the platform *w*, which is of course supported by any suitable construction, and is swept or shoveled into the said hopper, which is then turned by the attendant by means of the handle and shaft *p* to its dumping position. It 25 is evident from the description hereinbefore given that when the hopper has turned to its dumping position the wall *i*, or, more properly speaking, the edges thereof, will close the door-opening; but in the positions of the hopper 30 intermediate between the normal and the dumping positions there will be left an open space, and to close this I prefer to provide a metal hood *s*, which is curved on an arc of a circle struck from the said shaft *c* as a center 35 and is hinged to the front *e* at *t*. Said hood *s* is provided with a chain *u* and counterpoise *v*. After the hopper has been filled the attendant lowers said hood *s* to the platform *w*, and then said hood, together with the end 40 walls of the hopper, closes the door-opening and prevents the escape of the flames while the hopper *C* is in transit.

To admit air above the fuel, I provide 45 twyer-irons *x* in the front of the furnace, the same being a long rectangular perforated casting, as indicated in Fig. 2, and the brickwork is constructed as indicated in that figure.

The grates *m* are preferably inclined at such an angle that the fuel and ashes will slide 50 down as the fuel burns, and a door is pro-

vided at the side of the furnace, as indicated by dotted lines in Fig. 1, for the removal of the ashes.

While the drawings show the wall *i* as flat, I may belly the middle parts of it to form 55 what I term a "bag;" but in this case the edges will be flat and of a size and shape to close the furnace-door opening when the hopper is in the dumping position.

Now, having described my improvements, I 60 claim as my invention—

1. The combination with a furnace of a shiftable hopper having a wall adapted to close the furnace-opening when the hopper is in the normal position for being filled, and a 65 wall adapted to close said opening when the hopper is in the dumping position, and a hood hinged to the furnace-front and adapted to be lowered while the hopper is moving to said dumping position and close said door-opening, substantially as described.

2. The combination of a hopper having a wall constituting a door for the furnace-opening when the hopper is in the normal position for being filled, a wall constituting a door for 75 said opening when the hopper is in the dumping position, and walls having curved top edges as described, and a curved hood hinged to the furnace-front and adapted to be lowered over the hopper and together with said 80 curved ends close said door-opening in the intermediate positions of said hopper, substantially as described.

3. The combination with a furnace of a hopper having a wall adapted to close the furnace-opening when the hopper is in the normal position for being filled and a wall adapted to close said opening when the hopper is in the dumping position, a hood hinged to the furnace-front and adapted to be lowered 90 and close the said opening while the hopper is moving to the dumping position, a counterpoise for the hood, and means for shifting said hood, substantially as described.

Signed at New York city this 17th day of 95 December, 1900.

WILLIAM J. BALDWIN.
